UNITED STATES PATENT OFFICE.

FRANK MITCHELL AND CHARLES BEAL, JR., OF PHILADELPHIA, PENNSYLVANIA.

WIRE HEAD AND FASTENING MEANS FOR LOOMS.

No. 873,448.

Specification of Letters Patent.

Patented Dec. 10, 1907.

Application filed March 27, 1907. Serial No. 364,920.

To all whom it may concern:

Be it known that we, FRANK MITCHELL and CHARLES BEAL, Jr., citizens of the United States, residing at Philadelphia, in the county 5 of Philadelphia and State of Pennsylvania, have invented certain new and useful Improvements in Wire Heads and Fastening Means for Looms, of which the following is a specification.

10 Our invention relates to a new and useful means for fastening pile wires to the wire heads in tapestry or other looms, and the object of our invention is to provide simple and inexpensive means for fastening a pile wire 15 within its head, which will securely hold the wire and prevent the same from working loose, and which may be inserted within the head, and locked therein in a minimum of time.

20 Our invention consists in the following features of construction and arrangement as hereinafter described and pointed out in the accompanying drawings, in which,

25 Figure 1 is a perspective view of a wire head and a pile wire securely held therein according to our invention. Fig. 2 is a face view of a wire head constructed according to our invention. Fig. 3 is a sectional view on the line 3—3 of Fig. 2, looking in the direction of the arrow. Fig. 4 is an enlarged sectional view through the wire head showing the locking plug or rivet inserted therethrough preparatory to locking, and Fig. 5 is a similar view showing said plug or rivet inserted 35 through the wire head and locked.

30 In the practical embodiment of our invention we provide a wire head A, of substantially the ordinary construction, provided with the ordinary guide finger B at one end thereof and with the opening C for the reception of 40 a suitable hook, such as is employed for supporting the wires in the loom.

45 According to our invention we provide the head A with an opening 1, countersunk on both faces of the head to provide beveled edges 2. An elongated opening 3 is constructed through the wire head communicating with the opening 1, said opening 3 being adapted to receive a pile wire D when the 50 same is locked or being locked within the opening 1 as we contemplate.

55 We provide further a locking plug or rivet 4, preferably constructed of a soft malleable metal, and provided with a tapering flange 5 at one end thereof, and with a transverse opening 6 adjacent said flange.

The operation of locking the wire D within its head A is as follows: The end of said wire D is first inserted within the opening 6 of the plug 4, and said plug is then inserted through the opening 1 of the wire head, the wire D being thereby projected sidewise within the elongated opening 3 of the head. The plug 4 having been inserted within the opening 1, the flange 5 thereof conforming closely to 60 one of the beveled edges 2 of said opening, and the opposite end of said plug extending beyond the plane of the opposite face of the head A as will be clearly seen by reference to Fig. 4. The surplus portion of the plug 4 65 thus projecting from the head A is then mashed, by a suitable instrument, and the said surplusage is thereby spread to fill in against the other beveled edge 2 of the opening 1, and thus provide a surface flush with 70 the face of the head A, as shown particularly in Fig. 5. It will be seen that as said plug 4 is being mashed, as described, the pile wire D, projecting within the transverse opening 6 of said plug, will be tightly and securely 75 encompassed, and held therein.

Having thus fully described our invention we claim:

1. In a device of the character described, the combination with the head provided with 85 an opening therethrough, and a slot extending from the edge thereof and communicating with said opening, of a malleable metal plug adapted to be inserted through said opening, and provided with a transverse opening for 90 the reception of the end of the pile wire extending within said slot, substantially as described.

2. In a device of the character described, the combination with the wire head provided 95 with an opening therethrough, having beveled edges, and a slot extending from the edge thereof, and communicating with said opening, of a malleable metal plug adapted to be inserted through said opening, said 100 plug being provided with a tapering flange fitting against one of said beveled edges and with a transverse opening for the reception of the end of the pile wire extending within said slot, substantially as described.

105 In testimony whereof we affix our signatures in presence of two witnesses.

FRANK MITCHELL.
CHARLES BEAL, JR.
